UNITED STATES PATENT OFFICE.

WILLIAM Z. BROWN, OF ATLAS, ILLINOIS, ASSIGNOR OF ONE-HALF TO
GEORGE MANEWAL, OF BUCKLIN, MISSOURI.

POST-HOLE DIGGER.

SPECIFICATION forming part of Letters Patent No. 481,688, dated August 30, 1892.

Application filed January 22, 1889. Serial No. 297,193. (No model.)

To all whom it may concern:

Be it known that I, WILLIAM Z. BROWN, of 5
Atlas, in the county of Pike, State of Illinois,
have invented certain new and useful Im-
provements in Post-Hole Diggers; and I do
hereby declare the following to be a full, clear,
and exact description of the same, reference
being had to the accompanying drawings,
forming a part of this specification, and the
letters of reference marked thereon.

This invention relates to certain improve-
ments in post-hole diggers which are more
especially applicable to those in which two
sections are employed, pivotally connected to-
gether, and adapted to be closed while being
withdrawn from the hole and afterward
opened to release the dirt held between them.

The invention consists in a peculiar con-
struction of diggers of the class described,
whereby they are adapted to be rotated to
cause them to cut into the earth more rapidly
and in providing improved cutting points and
blades, with a plunger working between the
blades to cause the discharge of the dirt at
the proper moment.

The invention further consists in certain
novel details of construction and combina-
tions and arrangements of parts, to be herein-
after described, and pointed out particularly
in the claims at the end of this specification.

In the accompanying drawings, represent-
ing my invention, Figure 1 is a perspective
view of a post-hole digger constructed in ac-
cordance with my invention. Fig. 2 is a ver-
tical sectional view. Fig. 3 is a side eleva-
tion showing a modification. Fig. 4 is a side
elevation at right angles to Fig. 3, showing
one of the cutting points or shares removed.

Similar letters of reference in the several
figures indicate the same parts.

The digger is formed by two sections piv-
otally connected together at their upper ends,
with a handle B extended upward from each
section, by which the device is rotated and the
sections opened and closed. In the preferred
form the handles B are connected to the cir-
cular frame C, formed in halves pivoted to-
gether, with the blades and cutting points or
shares D removably united thereto by bolts.

Extending from side to side of the frame is a
bridge-piece E, both ends of said piece, of

course, being connected to the frame on one
side of the pivoted points in order to permit
of the free movement of the two sections, and
rigidly mounted in this bridge-piece is the 55
pointed rod or guide F, on which the plunger
G slides. The downward movement of the
plunger is limited by the piece H, connected
thereto and extending above the bridge E,
said piece also serving as a foot-rest for forc- 60
ing the plunger down to discharge the dirt,
as will be hereinafter more fully described.

The guide F may, if desired, be in the form
of a screw, as indicated in dotted lines, to as-
sist in forcing the cutting-edges into the earth; 65
but such construction is not essential to the
operation of the device.

As before mentioned, the pivoted sections
are preferably formed by the frame with the
blades and cutting-points removably secured 7c
thereto, and the preferred form of blades and
cutting-points is as follows: The blades I are
formed of circular sections of relatively thin
steel with openings in them to enable them
to grasp and hold the dirt more securely, and 75
the cutting points or shares, while of rela-
tively the same shape, are narrower and some-
what longer in order to cut in advance of the
blade. The bottom edges of both the blades
and shares are inclined upwardly toward the 80
rear in order to always present a sharp point
for cutting, and said edges being sharpened,
when a root or other similar obstruction is
met with, by reversing the rotation of the tool
it may be cut through without difficulty, as 85
will be readily understood. When the tool is
rotated backwardly, as described, it will be
noted that there are no projecting points to
catch against the roots or other obstruction,
the heels of all the blades being above the 90
level of the points.

By employing the construction described
it will be seen that the cutting points and
blades may be readily removed for sharpen-
ing or renewal when broken, thus greatly pro- 95
longing the life and utility of the implement.

The handles are so connected to the sec-
tions as that when the sections are open in
position for being forced into the earth they
will cross at a point about midway of their 100
length and form braces for each other while
the implement is being turned, thus relieving

the frame of a large part of the strain which would be thrown thereon and rendering it practical to rotate diggers in which the two sections are pivoted together without employing cumbersome braces. The outward movement of the sections is limited by a stop K on one of the handles, which extends into position for engaging the other handle, this stop also serving in some measure as an additional brace while rotating the implement.

If desired, instead of providing a stop, the handles may be located directly opposite each other and the upper ends bent, as shown in Fig. 3, so as to pass, thereby forming abutments M on both handles which engage and limit their movement. Where straight handles are employed, I preferably provide supplemental handles N, which are removably secured thereto by clips n, and project horizontally on each side, forming levers for rotating the digger.

The operation is as follows: The sections are opened and the device rotated in the direction to cause the blades to enter the ground. This causes the blades to sink in pushing the plunger, which rests on top of the dirt, up, and when in sufficiently deep the sections are closed, grasping the dirt firmly on all sides. The implement is then withdrawn from the hole and the sections opened to allow the dirt to fall out; but should the dirt stick between

the sections it may be easily pushed out by forcing the plunger down by the foot, as before described.

It is obvious that the details of construction 35 of the device may be changed without departing from the spirit of my invention.

Having thus described my invention, what I claim as new is—

1. In a post-hole digger, the combination, 40 with the sections pivoted together, of the bridge extending across one section and the plunger carried by the bridge, substantially as described.

2. In a post-hole digger, the combination, 45 with the frame formed in halves pivoted together and an operating-handle connected to each half, of the blades secured to the frames and the relatively small removable cutting-points independently secured to the frame in 50 advance of the blades, substantially as described.

3. In a post-hole digger, the combination of the sections pivoted together and formed of relatively small removable cutting points or 55 shares and the perforated blades, substantially as described.

WILLIAM Z. BROWN.
